UNITED STATES PATENT OFFICE

2,535,019

COMPRESSOR

Sverre Johan Steensen, V. Aker, near Oslo,
NorwayApplication October 29, 1945, Serial No. 625,318
In Norway April 29, 1942Section 1, Public Law 690, August 8, 1946
Patent expires April 29, 1962

1 Claim. (Cl. 230—146)

1

This invention relates to compressors with a piston, which moves eccentrically in relation to the interior cylinder wall, so that its contacting point against the cylinder wall moves constantly around the same. The ordinary construction is that the piston is fastened to a shaft which is located eccentrically relatively to the cylinder and is driven around in the same by means of a motor. Consequently the shaft must be guided tightly through one head of the cylinder.

This construction requires an extremely exact manufacture, and already after a very little tear of the cooperating surfaces of piston and cylinder, a leakage will take place, and the efficiency of the compressor will be decreased. Moreover, care must be taken for a tightening by stuffing box at the place where the piston shaft passes out from the cylinder. Also this will give rise to leakage.

The present invention has for its purpose a construction which is not afflicted with the drawbacks mentioned above, and which is particularly intended to be used in refrigerator cabinets for domestic use. The interior space of the compressor itself is hermetically sealed, whereas the motor is located outside the sealed system of compartment and conduits.

It has a simple and efficient execution and consequently is very cheap in manufacture and operation. This is obtained by the use of a strong magnet which rotates in relation to the non-magnetic cylinder outside the latter and thereby causes the contacting point of the magnetic piston to move as stated above.

Thereby a cylindric piston may be placed loosely into a cylinder with a larger diameter, a partition directed towards the center being fixed on the interior cylinder wall and meshing in a radial groove corresponding thereto and made in the piston in order to separate the suction side from the pressure side. Further, a preferably annular rotating magnet with pole shoes is arranged, said shoes travelling with a quite small margin around in the stationary cylinder.

Consequently there are no shafts or eccentrics and moreover no exact adaptation between the curved surfaces of the piston and the cylinder is required. The end faces of the cylinder may simply be adapted to each other by placing the top and bottom of the cylinder against the end surface of the piston and by soldering them to the periphery of the cylinder casing.

During the rolling or sliding of the piston against the cylinder wall the piston is pressed against this wall and will always provide a good

tightening contrary to what is the case when the piston is journaled around a pin, because in such a case it is always necessary to arrange a small distance which will gradually increase during 6 the use.

Further it is not necessary to let the said curved surfaces be circle-cylindrical surfaces. They can very well depart from this shape, although this would be less suitable owing to the 10 practical manufacture.

Another embodiment, wherein the rotor in known manner rotates on a pin arranged eccentrically in the interior of the cylinder and provided with one or more partitions guided radially in the piston and being maintained constantly in contact with the cylinder wall, may consist in the rotor of non-magnetic material 15 rotating loosely on the eccentric pin and the partitions of magnetic material travelling loosely in 20 their grooves acted upon by corresponding rotating magnets arranged outside the apparatus. Also this embodiment permits an hermetical sealing but is nevertheless less suitable.

In the drawing the two embodiments mentioned above are illustrated. Fig. 1 is a cross section through the compressor, and Fig. 2 a corresponding axial longitude section.

The cylinder wall which is made of non-magnetic material is for instance a thin bronze pipe, to which is soldered the endwalls 2, 2 which may be made of steel. One endwall is first soldered fast, whereafter the piston 4 of magnetic material and with a somewhat less diameter is inserted. Then the other wall is placed in position until it is in contact with the piston and is soldered fast in this position. Thereby the compressor itself is ready-mounted.

As will be seen from Fig. 1 the piston, which may have 3-4 mm. less diameter than the cylinder 1, and lies loosely within the same, may roll or slide along the inner wall surface of the cylinder, it being coupled together with the cylinder only by the fixed wing 3, which forms a partition between the suction and pressure side of the compressor. This wing 3 is fastened to the end-faces of the cylinder.

The ports 5 and 6 represent the suction and pressure channels, dependent upon the direction of rotation.

Around the cylinder a strong magnet 8 is mounted on a disk 9, which is fastened to the motorshaft 10, so that it rotates around the cylinder 1 with a quite small intermediary space, for instance 0.1 mm. The pole shoes 13 and 14 of the magnet attract the piston 4, so that it will

contact strongly against the cylinderwall, and the contacting point will move around according as the magnet rotates.

In this manner two separate compartments are formed, a suction and a pressure compartment.

These compartments increase or decrease in volume according as the magnet rotates, and the contacting point adjacent to the pole shoes of the magnet moves along the periphery, whereby the enclosed gas passes in through one and out from the other one of the ports 5 and 6. The interior of the compressor of course must be supplied with oil for lubricating and tightening the surfaces. The magnet may be an electric magnet with sliding contacts or a permanent magnet.

Of course not the whole piston 4 need be of magnetic material. It is sufficient that only an exterior cylindric ring is made of such a material, or the piston may be annular.

By very strong magnets it might occur that the pole-shoes attract the piston so strongly against the cylinderwall, that this in spite of the insignificant sliding may give rise to tear or to deformation of the thin-walled cylinder. This may be avoided by arranging inside the cylinder, as shown in Fig. 1, a stationary concentric pin 11 and by providing the piston with a bore 11', which is concentric with the piston but eccentric to the cylinder, whereby the attracting force of the magnet will be taken up by the pin 11 which in such case must be made exactly.

Besides, it is obvious that the magnet or magnets rotating around the pump housing, may be replaced by a plurality of stationary electromagnets arranged around the housing and the cur-

rent of which is closed in succession, so that a rotary magnet field is obtained.

I claim:

5 A compressor comprising a pump housing having an interior cylindrical space, a cylindrical rotor piston of a diameter different from that of interior space of the housing and located loosely and eccentrically within the housing, said piston being at least partly of magnetizable material, means outside the housing for producing a 10 rotary field of magnetic forces to cause the piston to contact at any time with said wall along an axially directed straight contacting line in rolling along said wall with the contacting line 15 travelling constantly around on the wall in accordance with the rotation of said magnetic field, an inlet port for the medium to be compressed, an outlet port for the compressed medium, and a partition arranged between the inlet and outlet ports so as to separate at any time the suction space of the pump from the compression space.
